A. B. DAVIS, OF PHILADELPHIA, PENNSYLVANIA, ASSIGNOR TO HIMSELF AND WILLIAM C. EWING, OF SAME PLACE.

Letters Patent No. 94,085, dated August 24, 1869.

IMPROVEMENT IN DUPLEX WRENCH.

The Schedule referred to in these Letters Patent and making part of the same.

To all whom it may concern:

Be it known that I, A. B. DAVIS, of Philadelphia, county of Philadelphia, and State of Pennsylvania, have invented an Improved Duplex Wrench; and I do hereby declare the following to be a full, clear, and exact description of the same.

My invention consists of a wrench, constructed in the peculiar manner fully described hereafter, so that it may be used as an ordinary wrench for square or six-sided nuts, &c., as well as for cylindrical objects.

In order to enable others skilled in the art to make and use my invention, I will now proceed to describe its construction and operation, reference being had to the accompanying drawing, which forms a part of this specification, and in which—

Figures 1 and 2 are exterior views of my improved duplex wrench;

Figure 3, a sectional plan, on the line 1-2, fig. 1; and

Figure 4, a sectional view of a portion of the wrench, drawn to an enlarged scale.

Similar letters refer to similar parts throughout the several views.

The shank A of the wrench is flattened upon its opposite sides, as best observed in fig. 3, has screw-threads *a*, and is furnished at one end with a suitable handle, *b*, while at its opposite end is the double permanent jaw B.

The movable jaw B' is arranged to slide upon the shank A, and has a slot, *c*, through which the said shank passes, of such a form that while it will prevent the jaw from turning upon the shank, it will permit it to have a slight play or vibration upon the same. (See figs. 3 and 4.)

From the jaw B project the two arms *ff'*, one on each side of the shank, the two arms terminating in a yoke, D, which is also arranged to slide freely upon the shank, the yoke containing a nut, F, the internal thread of which is adapted to the thread *a* on the shank, so that the jaw B' may be moved from or toward the jaw B, according to the direction in which the nut is turned.

On the bevelled face *h* of the movable jaw are formed serrations or teeth, opposite to the teeth on the stationary jaw B, the two sets of teeth being cut in such a manner that their points shall be directed toward each other, as clearly illustrated in fig. 4.

A spring, *i*, which is secured to the arm *f'* and ar-

ranged to bear against the shank, has a tendency to maintain the movable jaw in the position shown in figs. 1 and 3, or, in other words, in such a position that the end *x* of the slot *c* shall bear against the shank, this being the position in which (after the adjustment of the wrench) the serrated ends of the jaws are maintained at the greatest distance apart from each other.

Any force tending to compress the spring *i*, and to move the jaw B in the direction of the arrow, fig. 1, will cause the serrated surface of the movable jaw to approach that of the stationary jaw.

When a round pipe, such as that represented by the red lines *y* in fig. 4, or other cylindrical object is to be grasped and turned by the wrench, the movable jaw is adjusted, by means of the nut F, until the object is held between the two serrated surfaces, the wrench being then turned in the direction of the arrow, fig. 4, will cause the jaws to firmly gripe the pipe.

To release the pipe, all that is necessary is to turn the wrench in a direction contrary to that indicated by the arrow, fig. 4, which will enable the spring *i* to again so move the jaw B' as to withdraw its teeth from the surface of the pipe.

The jaw B', arms *ff'*, and block D, are made in one piece, and the nut is made slightly rounding, both above and below, so as to admit of the free vibration of the jaw B'.

While the instrument is a most available one for turning cylindrical objects, it is none the less serviceable as an ordinary wrench, for square or six-sided nuts, &c., for the projecting portions *m m* of the two jaws will act on such objects in the same manner as those of ordinary wrenches.

I claim as my invention, and desire to secure by Letters Patent—

A duplex wrench, consisting of the screw-shank A, its permanent serrated jaw B, the slotted serrated jaw B', its arms *ff'*, and yoke D, enclosing the nut F and the spring *i*, the whole being arranged and operating as herein described.

In testimony whereof, I have signed my name to this specification, in the presence of two subscribing witnesses.

A. B. DAVIS.
